LASTING MACHINE

Original Filed Feb. 15, 1926

INVENTOR
Robert J. Rice
By his Attorney,
Nelson Howard

UNITED STATES PATENT OFFICE

ROBERT J. RICE, OF JOHNSON CITY, NEW YORK, ASSIGNOR TO UNITED SHOE MACHINERY CORPORATION, OF PATERSON, NEW JERSEY, A CORPORATION OF NEW JERSEY

LASTING MACHINE

Original application filed February 15, 1926, Serial No. 88,270. Divided and this application filed October 2, 1929. Serial No. 396,765.

This invention relates to improvements in machines for use in the manufacture of shoes and is illustrated herein as embodied in a machine for lasting pre-welted shoes, that is 5 shoes in the manufacture of which the welt is attached to the upper before the upper is lasted.

It is an object of the present invention to provide an improved machine for working 10 the upper of a pre-welted shoe into lasted relation to an insole and a last on which the insole is mounted. While the illustrated machine, which constitutes a preferred embodiment of my invention, is particularly adapted 15 to use in the cement lasting of pre-welted shoes in accordance with the method of my application for Letters Patent of the United States, Serial No. 88,270, filed February 15, 1926, of which the present application is a 20 division, it should be understood that it may also be used for other purposes.

A feature of the invention comprises 25 means illustrated as a pair of gripper jaws adjacent to the fastening inserting instrumentalities of the machine for gripping the welt of a pre-welted shoe upper and holding the welt while the upper is worked into lasted 30 relation to the insole and last and while a fastening is inserted to secure the upper in lasted relation. Preferably and as illustrated 35 the sole gripping means and the fastening inserting instrumentalities are controlled by a single controller the displacement of which is effective first to operate the jaws and there- 40 after to cause the insertion of a fastening.

With the above and other objects and features in view the invention will now be described with reference to the accompanying drawings and pointed out in the claims.

45 In the drawings:

Fig. 1 is a side elevation of the head of a machine embodying the present invention; and

Fig. 2 is a fragmentary view on a larger 50 scale showing the manner in which a shoe upper is held at the time a fastening is inserted to secure the upper in lasted relation to the insole and last.

In Fig. 2, the numeral 2 indicates the insole and 4 a filler piece of a pre-welted shoe,

the margin of the insole being formed as shown at 6 to receive the upper 8 to the edge of which is stitched the welt 10. In the manufacture of pre-welted shoes by the method of my copending application, Serial 55 No. 88,270, water-dispersed rubber cement is applied to the exposed marginal portion 6 of the insole 2, to the edge of the filler 4, and also to the inner surface of the marginal portion of the shoe upper 8 and to the edge of 60 the shoe upper and welt 10. After the cement has been allowed to dry the insole 2 and filler 4 are secured to a last indicated at 11. The margin of the upper is then worked into 65 lasted relation to the insole and the last is temporarily secured in that position by tacks. The illustrated machine is well adapted to perform this lasting operation.

Fig. 1 discloses the head of the machine, which is a tacker of the type disclosed in Letters Patent of the United States, No. 1,106,393, granted October 11, 1914 on an application of Fred L. Mackenzie, provided, however, with gripping means adjacent to the nozzle of the tacker and with a controller 70 for actuating the gripping means and for thereafter causing the actuating of the tack inserting instrumentalities. The details of the tack inserting instrumentalities form no 75 part of the present invention and it is accordingly unnecessary to describe them at length herein. For a fuller description of those portions of the machine reference may be had to said Letters Patent. Briefly, the 80 mechanism comprises a driver 30 carried by a driver bar 32 arranged to slide vertically in a guideway in the front part of the head 34 of the machine, the driver bar 32 being lifted against the tension of a spring by a lifting cam on the front end of the main 85 shaft 36. The driving shaft is driven from a loose pulley 38 which may be clutched to the shaft at the will of the operator by suitable clutch mechanism controlled by a treadle 39 at the lower end of a treadle rod 40, as described in said patent. A tack pot 42 supplies tacks to a raceway 44 which conducts 90 them to a point adjacent to the nozzle 26 where they are separated one by one and delivered to the tacker nozzle 26 by suitable 95 100

tack separating mechanism 46 such as that disclosed in United States Letters Patent No. 1,312,557, granted August 12, 1919, on an application of Fred L. Mackenzie.

5. In accordance with my invention the machine is provided with a fixed jaw 22, shown as supported on a plate 48, introduced between the head and the column of the machine, and a movable jaw 24 attached to a lever 50 fulcrumed at 52 to the plate 48. The lever 50 has a long resilient rearward extension 53 lying in the path of movement of a screw 54 adjustably threaded through a block 56 which is attached to the treadle rod 40 so that 10 during the initial downward movement of the treadle 39 the jaw 24 will be caused to approach the jaw 22. The welt having been thus seized between the jaws, the shoe may be manipulated, as indicated in Fig. 2, to cause the cemented portions of the insole and filler to be brought into proper relation to the cemented portions of the upper and welt and pressed together, whereupon, by further depression of the treadle 39, the clutch will 15 be tripped and a tack 18 inserted through the nozzle 26 temporarily to hold the upper in lasted position, the rear portion of the lever 50 yielding sufficiently to permit tripping of the clutch. This operation is repeated progressively along the sides of the shoe from the heel breast line to the tip line.

After the shoe has been side lasted in the manner just described its heel and toe portions may be lasted in any suitable or desired 20 manner. After a suitable interval of time the lasting tacks may be removed.

Having thus described my invention what I claim is new and desire to secure by Letters Patent of the United States is:

40. 1. A machine for lasting pre-welted shoes having, in combination, fastening inserting instrumentalities, and means adjacent to the fastening inserting instrumentalities for gripping the welt of a pre-welted shoe upper and holding the welt while the upper is worked into lasted relation to an insole and a last on which the insole is mounted and while a fastening is inserted to secure the upper in lasted position.

50. 2. In a machine for lasting pre-welted shoes, the combination of a tacker having a nozzle, a jaw having a gripping face in the plane of the nozzle, a cooperating jaw, and means for relatively moving the jaws to seize the welt so that the insole may be brought into proper relation to the welt and a tack driven through the welt and upper into the insole and last.

60. 3. In a machine for lasting pre-welted shoes, the combination of a tacker having a nozzle, a fixed jaw adjacent to the nozzle having its gripping face in the plane of the end of the nozzle, a movable jaw cooperating with said fixed jaw, and a treadle connected to the movable jaw and also to the tacker so that

upon depression of the treadle the jaws will be operated to seize the welt and allow the insole and filler to be brought into proper relation to the welt and upper and upon further movement of the treadle the tacker will be actuated to insert a tack through the welt and upper into the insole and last.

70. 4. In a machine for lasting pre-welted shoes, the combination of a tacker having a nozzle, a fixed jaw adjacent to the nozzle having its gripping face roughened and located in the plane of the end of the nozzle, a movable jaw having a smooth face and a beveled end to enter the welt crease, and a treadle connected to the movable jaw and also to the tacker so that upon depression of the treadle the jaws will be operated to seize the welt and allow the insole and filler to be brought into proper relation to the welt and upper and upon further movement of the treadle the tacker will be actuated to insert a tack through the welt and upper into the insole and last.

75. 5. A machine for lasting pre-welted shoes having, in combination, fastening inserting instrumentalities, and a pair of jaws adjacent to the fastening inserting instrumentalities for gripping the welt of a pre-welted shoe upper and holding the welt while the upper is worked into lasted relation to an insole and a last on which the insole is mounted and while a fastening is inserted to secure the upper in lasted position, one of said jaws having a reduced end to enter the welt crease of the shoe.

80. 6. A machine for lasting pre-welted shoes having, in combination, fastening inserting instrumentalities, and a member adjacent to the fastening inserting instrumentalities having a thin edge formed and arranged to be received in the welt crease of a pre-welted shoe upper and to hold the welt and the marginal portion of the upper while the upper is worked into lasted relation to an insole and a last upon which the insole is mounted and while a fastening is inserted by said instrumentalities to hold the upper in lasted relation to the insole and last.

85. 7. A machine for lasting pre-welted shoes having, in combination, fastening inserting instrumentalities, a pair of jaws adjacent to the fastening inserting instrumentalities arranged to grip the welt of a pre-welted shoe upper and to hold the welt while the upper is worked into lasted relation to an insole and a last upon which the insole is mounted, one of said jaws having its end portion reduced to enter the welt crease of the shoe upper, and means for closing the jaws upon the welt and for thereafter causing the operation of the fastening inserting instrumentalities to insert a fastening to hold the upper in lasted relation to the insole.

90. 8. A machine for lasting pre-welted shoes having, in combination, fastening inserting

instrumentalities, a pair of jaws adjacent to the fastening inserting instrumentalities arranged to grip the welt of a pre-welted shoe upper and to hold the welt while the upper is worked into lasted relation to an insole and a last on which the insole is mounted, a treadle, and connections arranged when the treadle is displaced to close the jaws upon the welt and when the treadle is further displaced to cause the operation of the fastening inserting instrumentalities to insert a fastening to hold the upper in lasted relation to the insole.

10 In testimony whereof I have signed my name to this specification.
